Atty.

UNITED STATES PATENT OFFICE

HOMER F. LIVERMORE, OF BROOKLINE, MASSACHUSETTS, ASSIGNOR TO H. F. LIVERMORE CO., OF ALLSTON, MASSACHUSETTS, A CORPORATION OF MASSACHUSETTS

KNIFE FOR THREAD-CUTTING TEMPLES

Application filed May 9, 1931. Serial No. 536,151.

This invention relates to an improvement in knives for thread-cutting temples.

For many years it has been the custom to construct the movable knife of a well-known type of thread-cutting temple in such a manner that when the knife blades, of which there are two, become worn and need to be replaced, it is necessary for the user to discard the entire knife and replace the same with an entire new knife, or to return the worn knife to the manufacturer, in order that the blades may be replaced. In either case an unnecessary expense is incurred. This old-type knife, upon which there have been no improvements for many years, consists of a blade holder having a narrow arm, at the outer end of which it is necessary to mill two very narrow slots. A separate knife blade is located in each of these slots and the blades are first pinned and finally fused in their respective slots to the flanges. It is evident that this construction is unnecessarily expensive and as far as the users are concerned, it is necessary to replace the whole knife when, as a matter of fact, in most cases it is the blade only which needs replacing.

Another serious defect with the construction hereinbefore mentioned is that it is difficult to properly align the two separate blades and the users experience much difficulty because of the fact that they are forced to accept knives having blades that are improperly aligned. Furthermore, in the operation of the knife, a lower edge portion of the arm carrying the knife blades contacts with the temple bar and this lower edge which includes the lower edges of the three flanges and the two knife blades which, as before stated, may be improperly aligned, causes excessive wear both to the lower edge of the knife and the surface of the temple bar with which it contacts.

The object of this invention is to provide an improved knife for a thread-cutting temple constructed in such a manner that when the blades become worn they may be easily removed from the blade holder by the user without it being necessary to return the knife to the manufacturer.

Another object of the invention is to construct the knife blades from a single piece of steel, said blades being formed in such a manner that their cutting edges will always be in alignment both before and after the blades are attached to the holder.

The invention consists in a knife for thread-cutting temples as set forth in the following specification and particularly as pointed out in the claims thereof.

Referring to the drawing:—

Fig. 1 represents a side elevation of a portion of a thread-cutting temple, the knife of which is constructed in accordance with my invention, the temple roll and top member to which the roll is attached being removed in order that the blade of the knife will be exposed.

Fig. 2 is a plan view of a knife embodying my invention.

Fig. 3 is a side elevation of the knife.

Fig. 4 is a transverse section taken on the line 4—4 of Fig. 3.

Fig. 5 is a perspective view of the knife blade.

Like numerals refer to like parts throughout the several views of the drawing.

In the drawing, 6 is a temple bar, 7 a stand and 8 a cap for the bar and stand, all well known in the art. A knife 9 constructed in accordance with my invention is mounted in a well-known manner upon the temple bar 6 and a spring 10 has a coil portion 11 provided thereon which is seated upon a stud 12 which projects laterally from a side of the bar 6. An arm 13 of the spring 10 terminates in a loop 14 which is connected at 15 to the knife 9.

A stationary cutter 16 provided with a cutting edge 17 is attached to the front portion of the temple bar 6 in a well-known manner.

The knife 9 embodies therein a holder 18 provided with a downwardly projecting arm 19, a pair of laterally projecting flanges 20 and another pair of laterally projecting flanges 21, all of said flanges co-operating with a corner portion of the temple bar 6 to form a pivot for the knife. The holder 18, furthermore, has a narrow shank por-

tion 22 embodied therein to which a blade 23 is secured. The blade 23 is constructed of sheet material and is folded longitudinally thereof to provide parallel side portions 24, each of which is provided with a cutting edge 25. A portion 26 of the blade 23, which connects the side portions 24 thereof together, constituting a bridge portion which together with said side portions forms in cross-sectional contour a U. The side portions 24 of the blade 23 are provided with holes 27 which are adapted to align with similar holes provided in the shank portion 22 of the holder 18 to receive rivets 28 by means of which the blade is rigidly secured to the holder.

During the operation of the knife the holder portion 18 of said knife not only has a rocking movement imparted thereto upon the adjacent corner portion of the temple bar 6, but the upper surfaces of the flanges 20 have a sliding movement upon a lower surface 29 of said temple bar, and the bridge portion 26 of the knife blade contacts with a surface 30 of the temple bar, said latter surface constituting a stop and limiting the rocking movement of the knife 9 upon the temple bar 6.

The knife 9 of this invention is actuated in a manner well known to those skilled in the art by having the arm 19 thereof engaged by the lay of a loom during its beat-up movement. A rocking movement is first imparted to the knife, during which time the flanges 20 and 21 of the knife holder first have a rocking engagement with the adjacent corner portion of the temple bar 6. After the portion 26 of the knife blade has been moved into engagement with the surface 30 of the temple bar the action of the

lay in its contact with the arm 19 is to cause the knife to slide rearwardly upon the temple bar and the cutting edges 25 of the side portions 24 of the blade will co-operate with the cutting edge 17 of the stationary cutter 16 in a manner to sever the loose end of a filling thread, if there happens to be such a thread located between said cutters.

When the cutting edges 25 of the blade 23 become so worn that it is necessary to replace said blade, this may be easily accomplished by removing the rivets 28 and detaching the blade from the shank 22 of the blade holder, and replacing the old blade with a new one.

It will be seen that as the blade consists of a single piece of material the cutting edges 25 of both of the side portions 24 of said blade will always be located in alignment with each other and that there is no possible chance for either of said side portions or cutting edges to get out of alignment either when being attached to the holder or during the operation of the knife. Furthermore, as the blade 23 is constructed of a single piece of material, the bridge 26 will always be smooth, and excessive wear cannot take place between said bridge and the surface 30 of the temple bar.

I claim:

A knife for thread-cutting temples comprising a single piece of sheet material folded longitudinally thereof to form parallel side portions, each provided with a cutting edge, and a bridge portion extending longitudinally of said side portions and connecting them together along their lower edges to form a U.
